(57) **CLAIM**

The ornamental design for a sensor housing as shown and described.

DESCRIPTION

1. Sensor housing

1.1 : Front

1.2 : Back

1.3 : Top

1.4 : Bottom

1.5 : Left

1.6 : Right

1.7 : Perspective

1.8 : Perspective

1.9 : Perspective view showing the state in use

The present article is a compact sensor housing that is attached to a target factory equipment and is used for predictive maintenance thereof; the article contains a vibration sensor, an acceleration sensor, a temperature and humidity sensor, or the like therein for sensing a condition of the equipment and has a wireless communication function; the broken lines depict portions of the article that form no part of the claimed design; the alternating long and short lines define bounds of the claimed designs and form no part

(Continued)

thereof; the reproduction 1.9 is a perspective view showing a use state in which an attachment tool used for attachment to the equipment is attached.

1 Claim, 9 Drawing Sheets
